UNITED STATES PATENT OFFICE.

JAMES ADAIR, OF EDGEWORTH, PENNSYLVANIA.

DESIGN FOR A PEN-RACK.

SPECIFICATION forming part of Design No. 34,750, dated July 9, 1901.

Application filed February 13, 1901. Serial No. 47,188. Term of patent 14 years.

To all whom it may concern:

Be it known that I, JAMES ADAIR, a citizen of the United States, residing at Edgeworth, Leet township, in the county of Allegheny and State of Pennsylvania, have invented a certain new and original Design for Pen-Racks, of which design the following is a specification.

In the accompanying drawings, forming a part of this specification, Figure 1 is a plan view of my new design for a pen-rack, and Fig. 2 is an end elevation of the same.

The leading features of the design are the

base or foundation 1, having the shape and contour of a pen, and the spiral coils 2, forming the gripping-fingers, supported by the pen-shaped base or foundation.

I claim herein as my invention—

The design for a pen-rack as herein shown and described.

In testimony whereof I have hereunto set my hand.

JAMES ADAIR.
